(57) CLAIM

The ornamental design for an outdoor waterproof box, as shown and described.

DESCRIPTION

FIG. 1 is a perspective view of an outdoor waterproof box showing my new design,

FIG. 2 is a perspective view thereof from another angle.

FIG. 3 is a front elevational view thereof.

FIG. 4 is a rear elevational view thereof,

FIG. 5 is a left side elevational view thereof,

FIG. 6 is a right side elevational view thereof,

FIG. 7 is a top plan view thereof;

FIG. 8 is a bottom plan view thereof; and,

FIG. 9 is an enlarged view of outlined area 9 in FIG. 2.

The evenly dashed broken lines shown in the drawings represent portions of the outdoor waterproof box that form no part of the claimed design. The unevenly dashed broken lines shown in FIGS. 2 and 9, which form no part of the claimed design, outline portions of the outdoor waterproof box that are illustrated in enlargements.

1 Claim, 9 Drawing Sheets
